(57) **CLAIM**

The ornamental design for a glass for a watch caseback as shown and described.

DESCRIPTION

FIG. 1 is a first front view of a glass for a watch caseback showing my new design;

FIG. 2 is a first rear view thereof;

FIG. 3 is a second front view thereof;

FIG. 4 is a second rear view thereof;

FIG. 5 is a third front view thereof;

FIG. 6 is a third rear view thereof;

FIG. 7 is a fourth front view thereof;

FIG. 8 is a fourth rear view thereof; and,

FIG. 9 is a side view thereof.

The appearance of the image sequentially transitions between views shown in FIGS. 1, 3, 5 and 7 and FIGS. 2, 4, 6, and 8. The process or period in which one image transitions to another image forms no part of the claimed design.
